UNITED STATES PATENT OFFICE.

WILLIAM WHIGHAM, OF PITTSBURGH, PENNSYLVANIA.

DIPPING MECHANISM.

1,248,766.

Specification of Letters Patent.

Patented Dec. 4, 1917.

Application filed September 23, 1915. Serial No. 52,182.

To all whom it may concern:

Be it known that I, WILLIAM WHIGHAM, a citizen of the United States, and resident of Pittsburgh, in the county of Allegheny and State of Pennsylvania, have invented 5 certain new and useful Improvements in Dipping Mechanism, of which the following is a specification.

My invention relates to means employed 10 in handling glass articles, in dipping such articles into an etching solution, lacquer, or other liquid, and while not restricted to such use, more particularly in dipping electric light bulbs into a solution of hydrofluoric acid or similar etching compound or 15 solution, and in holding the articles in the solution while etching the outer surface of the glass.

Heretofore, it has been the practice to dip 20 such articles by hand, and as the articles must be maintained in the fluid for a short time, the hand dipping operation is slow and expensive, while it has been found difficult if not impossible to dip the successive lamp 25 bulbs into the solution to a uniform depth and to maintain the lamps in a vertical position while being dipped.

The specific gravity of the etching solutions or compounds is usually so great, 30 relative to the articles being dipped, as to make it necessary to hold the articles in position within the solution and prevent their lifting therefrom while the solution or compound 35 is acting upon the surface of the article being etched or coated.

One object of my invention is to provide 40 dipping apparatus having novel means whereby the articles are dipped successively into the etching solution to a pre-determined depth and are held therein for any desired time interval.

Another object of the invention is to provide 45 a dipping apparatus having novel means whereby the articles are maintained in a vertical position while being manipulated in the dipping operations, and whereby the depth to which the successive lamps are dipped is made uniform.

The invention consists in certain novel 50 features of construction and combinations and arrangements of parts, as hereinafter will be more fully described and specifically pointed out in the appended claims.

Referring now to the drawings forming 55 part of this specification, Figure 1 is an elevation partly in section showing a dipping

mechanism constructed and arranged and adapted for use in dipping incandescent lamp bulbs in accordance with my invention in etching such glass articles to impart the 60 desired frosted appearance to the surfaces of the articles.

Fig. 2 is a plan of the apparatus shown in Fig. 1.

Fig. 3 is a sectional end elevation showing 65 a modified form of apparatus as constructed and arranged for dipping larger articles of different contour.

Fig. 4 is a side elevation showing a detail 70 of the lamp centering mechanism shown in Fig. 1.

In the accompanying drawings the numeral 2 designates a base which may be the 75 top of a table or bench, or which (as shown) may be made of such size as to be readily placed in any desired location upon a table or bench. Secured on the base 2 so as to extend vertically, is a hollow stem or pedestal 3, and removably secured within the opening 4 of the pedestal so as to be adjustable relative thereto is the long end 5 of a bent arm or goose neck 6.

The upper end of the pedestal 3 is provided with a thumb screw 7 or equivalent device, by which the goose neck 6 is secured 85 in adjusted position on the pedestal, so as to prevent lifting movement thereof and also to secure it against rotation about the axis of the pedestal.

An adjustable ring or collar 8 which is 90 slidably mounted on one end of the goose neck 6 and is secured in adjusted position thereon by a thumb screw 9, provides means for limiting downward movement of the goose neck relative to the pedestal 3 and in 95 this way to regulate the distance the successive lamp bulbs 10 suspended from the short end 11 of the goose neck are dipped into the etching solution within the container 12 in using my improved apparatus.

The upper surface of the base 2 has a counterbored recess or hole 13 forming a rabbet in which the container or receptacle 12 for the etching solution, lacquer or other liquid into which the lamp bulbs or other 105 articles are dipped, is positioned, the container 12 in this way being positioned relative to the pedestal 3 so as to bring the successive lamps or other articles suspended from the goose neck 6 substantially into 110 alignment with the center of the container 12.

A bead 14 on the upper end of the container 12 forms a convenient gage to determine the height at which the solution is to be maintained within the container.

- 5 A spring clasp 15 on the pedestal 3 which encircles the top of the container also forms means for positioning the container relative to the pedestal. Both the recess and the spring clasps may be used, as shown, although obviously either may be omitted when desired. The container also may be permanently fastened to the pedestal, although preferably the container will be removably secured as has been described.
- 15 Secured to the short end 11 of the bent arm or goose neck 6 is a socket, a clamp or other means 16 for detachably securing and holding the lamp bulbs 10 or other articles in dipping position above the container 12.
- 20 As shown the socket 16 has internal threads 17 to fit the threads on the base 18 on the ordinary incandescent lamp bulbs 10.

As the bases on such incandescent lamps seldom are in axial alinement with the center 25 of the glass bulbs to which they are permanently fastened, to simply screw the base 18 of the lamps into the socket 16 will result in irregularity and variations in the depth to which the bulbs project into the 30 solution in the container, so that the successive lamps are not etched in the desired uniform manner.

To avoid this difficulty the socket 16 is provided with an annular sleeve 19 which is arranged to slide on the socket to bring its 35 lower end into engagement with the surface of the neck portion 20 of the lamps 10 so as to center the successive lamps by engagement of the end of the sleeve 19 with the 40 lamp necks 20 and in this way secure the successive lamps on the goose neck so as to extend in the desired vertical plane.

The sleeve 19 may be provided at separated intervals on its surface with a series 45 of slits 22, 22, so as to enable the sleeve to be frictionally held in position on the socket 16, or a set screw 23 may be used to fasten the sleeve in adjusted position on the socket and both may be employed when desired.

50 In the modification shown in Fig. 3, the construction is the same except that the clamp 24 on the short end 11 of the goose neck used in securing the articles to be etched or lacquered on the end of the goose neck 55 6 is somewhat different, a thumb screw 25 being employed to hold the article in vertical position between the jaws 26 and 27, and as the shape and size of the various articles etched or lacquered will differ from that of the incandescent lamp bulbs 10, the container 60 12 used with this apparatus is of increased length and depth and in such case the recess 13 in the upper face of the base 2 will be made of the same size and contour as the 65 outer side surface of the container, while a

spring clasp 15 will be used with or as a substitute for the recess 13, as is desired.

In the operation of my improved apparatus, two or more goose necks 6 will be used with each pedestal 3 and container 12, one being employed to hold an article 10 being etched in dipped position within the liquid, while an etched article on the other goose neck is being freed of excess solution and while the etched article is being removed 75 and being replaced on the goose neck by an unetched article.

After the lamp 10 or other article is screwed part way into the socket 16 on the short end 11 of the goose neck, the sleeve 80 19 is moved on the socket to bring its lower edge into engagement with the surface of the lamp 10. The long end 5 of the goose neck 6 is then inserted in the vertical opening 4 in the hollow pedestal. The opening 4 in 85 the pedestal forms a guide so that the goose neck moves vertically in a straight line and the lamp attached to the socket on the short end 11 of the goose neck is moved downwardly into the liquid in the container 12 in 90 a vertical line. The lamp is submerged with 95 in the solution in the container 12 to the desired depth and the thumb screw 7 on the upper end of the pedestal 3 is then tightened to fasten the goose neck in position to hold 100 the lamp in the desired position. The set collar 8 on the end 5 of the goose neck is then moved downwardly thereon until in engagement with the upper end of the pedestal 3 and the thumb screw 9 is then tightened 105 to fasten the set collar in such position on the goose neck 6.

After the lamp has been held in the solution for the desired time interval, the thumb screw 7 on the pedestal is turned to release 110 the goose neck and the goose neck is lifted to raise the now etched lamp bulb out of the solution and to remove the goose neck 6 from the opening in the pedestal 3.

A second goose neck 6 is then positioned 115 in the same manner as has been described, and while the lamp on the short end of this goose neck is held in the etching solution, any excess solution adhering to the first etched lamp bulb is scraped off the surface 120 of such lamp, after which the lamp bulb is removed from the goose neck and washed, and a new lamp bulb is placed in position on the socket of this goose neck. The second goose neck is then removed from the pedestal as has been described, the goose neck 125 having the unetched lamp then being placed in position on the pedestal 3, and as the set collar 9 engages with the upper end of the pedestal the depth to which this lamp is caused to extend into the solution is determined by the set collar 10, being the same as with the others.

Experience has shown that in etching lamps with a solution of hydrofluoric acid 130

or similar material, a thin layer of the spent acid in intimate contact with the glass clings tightly to the etched surface of the glass, and as this solution is viscous a film of the 5 solution of considerable thickness adheres to the spent layer in contact with the surface of the lamp. This outer layer not being in contact with the glass is not killed by contact with the glass and can be scraped off 10 and allowed to drip back into the container.

In the operation of the apparatus shown in Figs. 3 and 4 the steps will be the same as has been described.

The advantages of my invention will be 15 apparent to those skilled in the art. The goose neck forms a convenient means for handling the lamps and by the use of the apparatus described the successively etched lamps are immersed in the etching solution 20 to exactly the same depth so as to provide a uniformly dipped product. The goose neck and pedestal form guiding means by which the lamp is moved into the solution in a vertical line and the set screw on the 25 pedestal enables the successive lamps to be fastened in submerged position so that the buoyancy of the electric light lamp will not cause it to lift out of the solution, as would otherwise be the case.

Modifications in the construction and arrangement of the parts may be made without departing from my invention as defined in the appended claims.

I claim:—

35 1. Dipping mechanism comprising a liquid containing vessel, a vertically slidable goose neck having means on one end for suspending articles above said vessel, and means for holding the slidable goose neck in position 40 relative to said vessel.

2. Dipping mechanism comprising a liquid containing vessel, a vertically slidable goose neck having means on one end for suspend-

ing articles above said vessel, a pedestal connected to said vessel on which said goose 45 neck is slidably mounted, and means for fastening the goose neck in position on said pedestal.

3. Dipping mechanism comprising a liquid containing vessel, a vertically slidable goose 50 neck having means on one end for suspending articles above said vessel, a pedestal connected to said vessel on which said goose neck is slidably mounted, means for fastening the goose neck in position on said pedestal, and adjustable means on said goose neck engaging with the pedestal for limiting the downward movement of the vertically 55 slidable goose neck.

4. Dipping mechanism comprising a base, 60 a liquid containing vessel thereon, spring means for yieldingly connecting said vessel to said base, a vertically movable goose neck having one end adjustably secured to said base, means on the other end of said goose neck for suspending articles above said vessel, means for fastening the goose neck in adjusted position on said base, and means adjustably secured on said goose neck and arranged to engage with said base for limiting the vertically downward movement of 70 said goose neck.

5. Dipping mechanism comprising a liquid containing vessel, a vertically movable goose neck having one end slidably mounted on the vessel, means on the other end of said goose neck for suspending articles above said vessel, means for fastening the goose neck in adjusted position on said vessel, and means on said other end of the goose neck 80 for alining vertically the articles suspended from said goose neck.

In testimony whereof I have hereunto set my hand.

WILLIAM WHIGHAM.
